UNITED STATES PATENT OFFICE

ORAZIO ALFREDO ALGENI, OF PROVIDENCE, RHODE ISLAND

FIRE-ALARM APPARATUS.

1,206,644.

Specification of Letters Patent. Patented Nov. 28, 1916.

Application filed November 27, 1915. Serial No. 63,871.

To all whom it may concern:

Be it known that I, ORAZIO ALFREDO ALGENI, a citizen of Italy, and residing at 105 Gray street, Providence, Rhode Island, United States of America, have invented a new and useful Fire-Alarm Apparatus, of which the following is the specification.

My invention relates to automatic fire-alarm apparatus and consists of an improved thermostatically-controlled circuit-closing device for sounding an electric bell or other annunciator.

The object of my improvement is to provide a simplified form of mechanism for the purpose described, capable of sensitive response under the effect of heat, and proof against derangement or getting out of order.

The manner and means for carrying out the improvement are fully described in the following specification, illustrated by the accompanying drawings, in which like reference characters designate like parts.

In the drawings:—Figure 1 is a vertical, sectional view of the complete apparatus; and Fig. 2, a plan view of the same.

Referring to the drawings, the operating elements of my improved circuit-closing device are inclosed in a cylindrical shell or cup-shaped casing A which is preferably constructed of porcelain, glass or other vitreous material of a non-conducting nature. Fitted to the upper rim of the casing A are two separate, arcuate strips or segments H, H of copper or other conducting material, bent over the sides of the rim and held in place thereon by screws or pins D, D impinging thereagainst. Connected with the screws or pins D, which serve as binding-posts, are the positive and negative wires K, K of an electrical circuit including a battery or other source of current and a bell, gong or similar annunciator, not herein shown.

Depending from the rim-members H, H within the casing A are two flat metal strips or arms G converging toward each other and bent at right-angles at the bottom with their ends spaced slightly apart. As shown in Fig. 2, the opposite extremities of the right-angled portions of the arm G are notched to receive between them a slidable rod C. Preferably the rod C is constructed of glass, or some other non-conducting material such as rubber or vulcanite, and has fastened across its upper end a strip of metal or other conductor B, adapted to serve

as a contact-member for connecting the terminals G.

At its bottom the casing A is formed with a central opening surrounded by a depending flange, similar to the neck of a bottle, and threaded on its interior. Screwed into the neck or flange of the casing A is a hollow plug or stopper F provided with a central opening adapted to serve as a receptacle for a charge of paraffin E or any other similar, fusible material. Preferably the plug F is constructed of aluminum or other metal having heat-conducting properties. The charge of paraffin E is normally maintained in a solidified state with the end of the vertical rod C resting upon it to hold the cross-plate or contact-strip B raised above the two terminals G.

The method of operation of the complete apparatus is as follows:—The shell or casing A is placed in any convenient position within the building, ship or other location to be protected from fire and may be suspended from the ceiling or fastened in any other suitable manner to maintain its axis vertical. The plug F is then filled with paraffin or a similar substance which will remain solidified under normal temperatures. In some cases where the device is to be located in a building heated above the normal temperature, or in a warm climate, sand or other particles may be mixed with the paraffin to raise the melting point of the charge. The plug F is filled about half full, as shown in Fig. 1, and when it is inserted in the neck of the casing A it will raise the rod C to lift the contact-member B away from the terminals G. Now, should a fire break out adjacent the apparatus the heat created thereby will fuse or melt the charge E of paraffin, or other substance, and this will allow the rod C to drop between the terminals G. The dropping of the rod C brings the contact-member B against the ends of the terminals G, thereby completing the electrical circuit through the wires K, K and causing the alarm to be sounded through the bell or other annunciator as usually provided.

I am aware that it is not new in the art to employ a circuit-closing device arranged to act automatically from the effect of heat. Various and sundry such arrangements have heretofore been proposed, but in my present improvement the mechanism of the device is much simplified, its action rendered more

2
reliable, and its parts better protected from derangement or hindrance from operation. With the casing or container A constructed of glass the mechanism may be inspected 5 from time to time without taking it apart, while its parts are adequately protected from dirt and dust and also against tampering with by unauthorized persons. That is to say, when the casing is attached to a ceiling 10 or other overhead support the parts of the apparatus are inclosed against outside interference, while still being visible for inspection. It will also be observed that very few parts are required for the operating mechanism of my improved apparatus, and these 15 being of simple construction and easy to manufacture the cost of the device is reduced to a minimum, rendering its employment in multiple for different parts of a 20 building very economical.

What I claim for my invention is:—

1. In an improved thermostatic circuit-closing device, the combination with a cup-shaped casing having an opening in its bottom, of a hollow stopper in said opening 25 adapted to receive a charge of fusible substance such as paraffin, two terminals depending from the rim of the casing within its interior and connected with an electrical 30 circuit, a rod of non-conducting material supported by the terminals to slide between their ends and normally arranged with its lower end resting on the fusible charge in the stopper, and a contact-piece carried at the 35 upper end of the rod to adapt it to make contact across the terminals when the charge fuses and allows the rod to drop.

2. In an automatic circuit-closing apparatus, the combination with a cup-shaped 40 shell of non-conducting material such as

glass, two separate segments of conducting material secured to the rim of the shell and connected to the wires of an electrical circuit, terminals depending from said segments within the shell with their ends spaced 45 apart, a non-conductor rod arranged to slide vertically in notches in the ends of the terminals, a contact-member at the upper end of the rod adapted to connect the terminals in circuit, and a plug secured in the bottom of the shell and carrying a charge of fusible material adapted in its solidified state to support the rod in raised position with the contact-member held clear of the terminals. 55

3. In a circuit-closing apparatus, the combination with a cylindrical casing of vitreous material having an opening in its bottom, of a hollow metal plug screwed into said opening to adapt it to hold a charge of fusible 60 substance in a solidified state, metal strips bent over the rim of the casing and fastened thereto in spaced-apart relation, binding-posts on said strips for connecting electrical conductors therewith, arms extending downwardly from the strips within the casing and bent toward each other to form spaced apart terminals at their ends, a vertical rod of non-conducting material slidably supported between the ends of the terminals with its 65 lower end resting on the fusible charge in the plug, and a contact-member mounted on the upper end of the rod to be normally supported thereby free from contact with the terminals. 70
